H. Lee Stevens

UNITED STATES PATENT OFFICE.

ARTHUR REGINALD VON KELLER, OF BROOKLYN, NEW YORK.

DRAINING CURBSTONE.

Application filed June 23, 1926. Serial No. 117,926.

The object of the present invention is to provide a curbstone which shall in general appearance and dimensions be the same as the usual street curb now employed and which shall be replaceable with the latter. The particular object of the invention is to provide a curb so constructed that it will dispose of refuse flushed against it, that side of the curb adjacent the street and projecting above it being formed with an opening or spaced openings to receive the dirt and water. The curbstone will be manufactured in suitable lengths, and will be placed end to end in the usual manner so as to lead the refuse to catch-basins usually situated at the corner or centre of the block.

The invention will be understood by reference to the accompanying drawing, in which—

Figure 1 is a perspective view of a short section of curbstone constructed in accordance with the invention, and

Figure 2 is a transverse section through one of the curbstones and a sidewalk and street section, showing the manner in which the curbstone is positioned relatively to the street and sidewalk.

By reference to the accompanying drawing it will be seen that the curbstone A may be constructed of reinforced concrete or other suitable material. The face of the curb which lies adjacent the sidewalk may be vertical, in accordance with the usual practice, or it may extend at an angle, as desired. The face of the curb adjacent the street likewise may be vertical, when in position. Said face may be formed with a plurality of openings a, the bottoms of which are so placed as to lie at the street level, so that refuse flushed toward the curb may readily pass through the opening and into the inner longitudinal passageway b. Passageway b is gradually restricted toward its upper end so that the overhanging substantially horizontal upper wall shall be strongly supported. In other words, the left hand inner wall of passageway b is so formed as to have the effect of a strut extending toward the upper right hand portion of the curb.

The lower wall c may be graded, for example one-eighth inch to the foot length, so that water will run off, carrying refuse with it, on streets that have not a natural grade.

I am aware that various attempts have been made by others to provide draining curbstones, but such attempts have not been successful when they were designed to receive refuse from the flushing of streets, because they were either inherently weak in construction and were not capable of replacement for the standard curbstones without alteration of street and sidewalk. By my invention a curb is formed which has the same general appearance, size and dimensions of the standard curbstone, which is inherently strong, which will adequately serve the purpose for which it is designed and involve a cost of manufacture very little, if any, greater than the usual cast solid concrete curbstone.

Having described my invention what I claim and desire to secure by Letters Patent is as follows:

1. A draining curbstone formed of concrete or the like and having substantially parallel side walls merging at their tops into a substantially horizontal top wall structure, the curbstone having a longitudinal internal passageway communicating with a plurality of openings in one side wall adapted to lie approximately at the street line.

2. A draining curbstone formed of concrete or the like, substantially rectangular in cross section and having its top wall substantially horizontal and forming a connecting top closure for the side walls, said curbstone having an internal longitudinal passageway, said passageway in cross section having one wall substantially parallel with a side wall, and a converging opposite wall, one wall being formed with an opening placed to lie approximately at the street line, as and for the purpose set forth.

In testimony whereof I have signed my name to this specification.

ARTHUR R. VON KELLER.
